Des. 197,684
Patented Mar. 10, 1964

197,684

ROLLED FABRIC DISPENSER

Virgil E. Gray, 1033 Haverhill Road,
West Sacramento, Calif.

Filed July 30, 1962, Ser. No. 71,076

Term of patent 14 years

(Cl. D80—1)

FIG. 1.

FIG. 2.

FIG. 3.

I claim:

The ornamental design for a rolled fabric dispenser, as shown.
